UNITED STATES PATENT OFFICE

112,974

DESIGN FOR A RANGE OR SIMILAR ARTICLE

Alfons Barnsteiner and Donald L. Hadley, Mansfield, Ohio, assignors to Westinghouse Electric & Manufacturing Company, a corporation of Pennsylvania

Application April 6, 1938, Serial No. 76,332

Term of patent 7 years

To all whom it may concern:

Be it known that we, Alfons Barnsteiner and Donald L. Hadley, citizens of the United States, residing at Mansfield, in the county of Richland and State of Ohio, have invented a new, original, and ornamental Design for a Range or Similar Article, of which the following is a specification, reference being had to the accompanying drawings constituting a part hereof, in which:

Fig. 1 is a front perspective view of a range or similar article showing our new design;

Fig. 2 is a top plan view thereof;

Fig. 3 is an enlarged fragmentary side view of the timer, back splash panel and a portion of the range top shown in Fig. 1; and

Fig. 4 is an enlarged front view of the timer shown in Fig. 1.

The dominant features of our design reside in the portions shown in full lines.

This application is a continuation-in-part of application Serial No. 73,488, filed December 9, 1937.

We claim:

The ornamental design for a range or similar article, substantially as shown and described.

ALFONS BARNSTEINER.
DONALD L. HADLEY.
